UNITED STATES PATENT OFFICE.

GUSTAV BRISKER, OF KÖNIGSHÜTTE, GERMANY.

MACHINE FOR ROLLING METAL PLATES AND BARS.

SPECIFICATION forming part of Letters Patent No. 437,970, dated October 7, 1890.

Application filed October 23, 1889. Serial No. 327,881. (No model.)

To all whom it may concern:

Be it known that I, GUSTAV BRISKER, a subject of the Emperor of Austria-Hungary, and a resident of Königshütte, in the Empire of 5 Germany, have invented certain new and useful Improvements in and Relating to the Rolling of Metal Bars, Plates, and the Like and to Apparatus Therefor, of which the following is a specification.

10 The improvements forming the subject of this invention consist in so arranging two-roller or three-roller mills that as the metal emerges from the pair of rolls whose action it is undergoing it is bent by one or more guide-rolls capable of a rising-and-falling motion in such a manner that, passing over the upper roll in two-roller mills or between the middle and upper roll in three-roller mills the metal is brought round again to the front side of 15 the mill. As soon as the whole piece is thus delivered at the front it is caused to pass again through a pair of rolls—*i. e.*, between the upper and lower or middle and lower rolls, as the case may be. The rising and falling 20 guide-rolls may be arranged in a variety of ways, provided always that the arrangement is such that after each passage between the rolls the metal piece is either bent and carried back to the front or may issue in a 25 straight shape behind the rolls. When a table or a platform is arranged at the back of the rolls, capable of being raised, as in mills for sheet-iron and iron of all sections, it can, if desired, (and without any special preparation,) be made use of for raising and carrying 30 back the metal each time the same emerges from between a pair of rollers. This arrangement, applicable to each of the different types 35 of mills hereinafter described, enables the metal to be subjected to the bending operation after it emerges from one pair of rolls, or to be left straight, at will, no matter at what rate of speed the rolling is carried on. In the case of three-high rolls the tail or end of the 40 rolled and bent metal piece is enabled by the peculiar construction and operation of the rising and falling guide-rolls to freely increase 45 in width toward the back. The invention is illustrated in the accompanying drawings, in 50 which—

Figure 1 represents a sectional side elevation of a two-roller mill. Fig. 2 is a similar

view of a three-roller mill. Figs. 3, 4, 5, and 6 are sectional side views of two-roller or three-roller mills, showing modifications of the 55 guide-rollers. Fig. 3^a is a detail view.

The arrangement of the guide-rolls is susceptible of the following variations:

First. A roller *w* may be raised or lowered by a cylinder *c*, as in the construction illustrated in Fig. 1. Before the metal piece leaves the rolls at the back the guide-roll *w* is slightly raised, and thereby imparts to the emerging metal an upward bend, and as the metal further emerges the roll *w* continues to ascend 60 and to bend the same so as to cause it to pass between the upper working-roll and what may be called a “dragging-roller” *x*, or, in the case of a three-roll mill, between the middle and upper roll. The plate *r* prevents the metal 70 from rising too high. By means of a stripper *a* and the straightening-roll *x* the metal piece as it emerges on the front side is straightened again. When it has passed to the front side, as explained above, the roller *w* sinks to the 75 level of the table again.

Second. The guide-roller *w* may also, as shown in Fig. 5, be connected with the lifting-table and rise and fall in conjunction with the latter.

Third. Two or more rising and falling guide-rollers *w* and *w'* may be provided, instead of one, as shown in Fig. 2, and adapted to move up and down either simultaneously or independently of each other.

Fourth. Rollers *w* *w'* may also, as illustrated in Fig. 3, be connected by a curved link *b*. The roll *w* in this case is loose on its shaft, which is fitted with eccentric fixed pivots *z*, Fig. 3^a. Before the metal piece emerges 90 from the pair of rolls the link *b* is turned on the pivots *z* and raised by the cylinder *c*, whereby, owing to the eccentric situation of the said pivots, the roll *w* is also slightly raised. The metal is then bent in a manner both simple and effective and conducted to the upper working-rolls, and as soon as it is grasped or seized by the rolls the link *b* is allowed to drop, so that the guide-rolls are brought back to the level of the table. In case it is desired that the metal should pass directly out from the lower rollers in a straight shape, these guide-rollers form part of the table.

Fifth. Guide-rollers *w* *w'*, connected by a

link, as aforesaid, may, if desired, be further connected with the table, as illustrated by Fig. 6, and rise and fall with the same. Before the metal leaves the rollers the table is, in this instance, raised to the position indicated in full lines, where it remains as long as it is desired that the metal piece should be carried back to the front of the machine. When it is deemed necessary that the piece of metal, either finished or not, should come out from between the working-rolls at the back in a straight shape, the table is allowed to sink, as indicated by dotted lines, just before the metal emerges.

15 Sixth. One of the guide-rolls *w* may be arranged behind the strippers of the lower working-roller, Fig. 4, and turn loosely on a shaft, the pivots of which are fixed eccentric similarly to those shown in Fig. 3^a. A link *b*, carrying another guide-roller *w'*, is hinged to the plate *r* and caused to rise and fall by a cylinder *c*. Before the metal leaves the rolls the roll *w* is caused by a suitable lever to turn through an angle of one hundred and eighty degrees, and, owing to the eccentric position of its shaft, it is thereby slightly raised, while at the same time the link *b*, with the roll *w'*, is allowed to descend, so that here again the passage of the metal from the back 25 to the front of the machine takes place in an easy and efficient manner. In case this arrangement is applied to a three-roll mill, the roll *w* after the passage of the metal is moved back to its original position, while the roll *w'* rises with the link *b*, so that nothing prevents the tail of the metal piece carried to the opposite side from increasing in width toward the back.

30 By means of the above-described modifications of my improved guiding arrangement of rolling-mills the following advantages are obtained in the manufacture of sheet-iron, iron of all sections, bars, billets, and the like:

First. In the devices hitherto used for conveying the rolled metal from one end of the machine to the other (the application of which was practically confined to wire and thin iron bands, these machines being unfit for other purposes) the same metal piece is 45 only carried over once. In my improved mill, on the contrary, all iron pieces capable of being worked in a rolling-mill, irrespective of width or thickness, including sheet-iron and iron of all sections, may be in the same way 50 guided backward and forward, and the metal is after each passage between the rolls caused to go through the same guiding contrivance. In the case of grooved rolls, the metal may by 55 the same means be shifted from one pattern-roll onto the other. Besides, each time the metal emerges from a pair of rolls it may at 60 will be made to go through the bending and guiding mechanism described or allowed to leave the working-rolls at the back, which 65 choice is not allowable in any of the systems hitherto known.

Second. In rolling iron of all sections and

sheet-iron with the assistance of the bending and guiding device the metal being alternately bent and straightened is freed from any slag or scales that may adhere thereto. Besides, each time it passes between the rollers it is turned over, so that the upper surface at the time is not the same which was turned upward during its preceding passage between the rolls. By this means either side of the metal sheet or band may in turn be scraped and freed from any impurities, which enables a better quality of sheet-iron to be turned out and diminishes the waste.

Third. In rolling flat bars or bands by means of grooved rolls the necessity of turning round the metal piece at an angle of one hundred and eighty degrees every time it leaves the pair of rolls, to avoid the formation of burr, is obviated.

Fourth. Owing to my guiding device, a different end of the metal piece is first inserted between the rolls each time, even in double or two-roller mills, so that it is uniformly rolled in either direction exactly in the same way as if the mill were a three-roll one.

Fifth. The arrangement herein described enables the production to be increased with a considerable reduction in the cost of labor.

I claim as my invention—

1. In a rolling-mill, the combination of the working-rolls with a movable return-guide, devices, substantially as described, for moving it during the rolling either into position to cause the metal to return to the front of the rolls to be rerolled or into position to permit the metal to pass out straight, all substantially as described.

2. In a rolling-mill, the combination of the working-rolls with a movable return-guide, and a motive-power cylinder to move the guide into position during the rolling, whereby the metal may be caused to return to the front of the rolls to be rerolled or into position to permit the metal to pass out straight, all substantially as described.

3. In a rolling-mill, the combination of the working-rolls with a movable return-guide forming part of the table or platform when at rest, and means for moving the guide into position to cause the metal to return to the front of the rolls to be rerolled or into position to permit the metal to pass out straight, all substantially as described.

4. In a rolling-mill, the combination of the working-rolls with a movable return-guide connected to the table or platform, and means for moving the guide into position to cause the metal to return to the front of the rolls and to be rerolled or into position to permit the metal to pass out straight, all substantially as described.

In testimony whereof I have affixed my signature in presence of two witnesses.

GUSTAV BRISKER.
